DESIGN FOR A SHOE OR SIMILAR ARTICLE

Vincent De Liso, Astoria, Long Island, N. Y.

Application February 27, 1939, Serial No. 83,230

Term of patent 3½ years

To all whom it may concern:

Be it known that I, Vincent De Liso, a citizen of the United States, residing in Astoria, Long Island, New York, in the county of Queens, in the State of New York, have invented a new, original, and ornamental Design for a Shoe or Similar Article, of which the following is a specification, reference being had to the accompanying drawing, forming part thereof.

The dominant feature of my design for a shoe resides in the heel set of the same as shown in solid lines.

I claim:

The ornamental design for a shoe or similar article, substantially as shown and described.

VINCENT DE LISO.
